(No Model.)

P. MEDART.
BELT TIGHTENING MECHANISM.

No. 448,583.

Patented Mar. 17, 1891.

FIG. 1.

FIG. 2.

FIG. 3.

ATTEST:

Geo H Arthur

W. H. Holmes

INVENTOR:

Philip Medart,

Robert R. Birne
Attorney.

UNITED STATES PATENT OFFICE.

PHILIP MEDART, OF ST. LOUIS, MISSOURI, ASSIGNOR OF ONE-HALF TO
WILLIAM MEDART, OF SAME PLACE.

BELT-TIGHTENING MECHANISM.

SPECIFICATION forming part of Letters Patent No. 448,583, dated March 17, 1891.

Application filed July 7, 1890. Serial No. 357,997. (No model.)

To all whom it may concern:

Be it known that I, PHILIP MEDART, a citizen of the United States, and a resident of the city of St. Louis, in the State of Missouri, have invented certain new and useful Improvements in Belt-Tightening Mechanism, of which the following is a specification.

This invention relates to mechanism for tightening the driving-belts of machinery, so as to increase the tension of the same and avoid slipping.

The object of the present improvements is to provide a tension mechanism in which are embodied the features of strength, simplicity, and durability combined with ease of adjustment and capability of being used in either a vertical, horizontal, or other position. I attain such object by the construction and arrangement of parts illustrated in the accompanying drawings, in which—

Figure 1 is a front elevation of a belt-tightening mechanism embodying my present improvements; Fig. 2, a side elevation of the same, and Fig. 3 a detail side elevation illustrating the adjustment of the boxes for a horizontal use of the mechanism.

Similar numerals of reference indicate like parts in the several views.

As represented in the drawings, my improved mechanism consists of parallel guides 1, supported at their ends by angle-brackets 2 and 2' and forming a slideway for the frame or carriage 3, upon which the tightening-pulley 4 is supported in suitable boxes or bearings 5, an adjustment of the carriage upon the slideway being effected by a central screw 6, bearing at its lower end against the carriage, with its upper end arranged to pass through a nut 7, arranged in a recessed hub 8, located centrally on the connecting-web 9, that unites the two upper brackets 2 together, as illustrated in Fig. 2. A suitable hand or capstan wheel 10 is secured to the screw 6 near its lower end for convenience in turning the screw to effect an adjustment.

In the present invention individual angle-brackets 2' are employed to support the lower ends of the guides 1, so that a clear way for the carriage 3 will be left at the lower end of the slideway. The parallel guides 1 will in the pres-

ent invention consist of rods having either a circular, square, or othersuitable cross-section, with their ends securely attached in the projecting hubs 11 of the angle-brackets 2 and 2', so as to hold the parallel guides 1 a suitable distance away from the wall or posts to which the tightener is attached, and give sufficient space for the movement of the guide bosses or sleeves 12, arranged on the back of the carriage 3, and which surround the parallel guides 60 and slide thereon in the movement of the carriage; and in the present invention said carriage or frame will be of a bifurcated or saddle form, consisting of cross top member 13 and pendent side members 14, to which the boxes 65 5 of the tightening-pulley 4 are attached in the following improved manner:

15 is a circular yoke or hanger-frame having a sole-plate 16, by which it is secured to its member 14, and a series of radially-arranged bosses 17, having screw-threaded orifices for the passage of the radially-arranged bolts 18, by which the box is held in place, and its adjustment to a proper position is effected, the usual lock-nuts 19 being used to lock the 75 bolts at their required adjustment in effecting a parallel alignment of the pulley-shaft, and a feature of the present invention is the arrangement of such bolts in pairs at right angles to each other, as shown, so that the self-oiling boxes 5, which are preferably employed in the present appliance, may be shifted around from the position shown in Fig. 2 to that shown in Fig. 3, when the appliance is changed from a vertical to a horizontal position, the object being to bring the reservoir portion of the box into the proper horizontal position.

Having thus fully described my said invention, what I claim as new, and desire to secure by Letters Patent, is—

1. A belt-tightening mechanism comprising, in combination, a slidable carriage provided with guide-sleeves on its back, a tightening-pulley mounted in boxes thereon, a 95 slideway for such carriage, consisting of parallel guide-rods that pass through the guide-sleeves of the carriage and attaching angle-brackets that support the guide-rods in a position away from the wall or posts, and an ad- 100

justing-screw forming an adjustable connection between the carriage and slideway, substantially as set forth.

2. A belt-tightening mechanism comprising, in combination, a slideable carriage provided with guide-sleeves on its back, a tightening-pulley mounted in boxes thereon, a slideway for such carriage, consisting of parallel guide-rods that pass through the guide-sleeves of the carriage, individual lower angle-brackets, and connected upper angle-brackets

formed with a central hub for the adjusting-screw, and an adjusting-screw forming an adjustable connection between the carriage and slideway, substantially as set forth.

In testimony whereof witness my hand this 30th day of June, 1890.

PHILIP MEDART.

In presence of—

BENJ. A. SUPPAN,

GUSTAVUS A. BUDER.
